UNITED STATES PATENT OFFICE.

ANDREW EKMAN, OF GRAND RAPIDS, MICHIGAN, ASSIGNOR TO GRAND RAPIDS BRASS COMPANY, OF GRAND RAPIDS, MICHIGAN, A CORPORATION OF MICHIGAN.

LATCH FOR REFRIGERATOR DOORS AND THE LIKE.

Application filed May 31, 1924. Serial No. 717,012.

To all whom it may concern:

Be it known that I, ANDREW EKMAN, a subject of the King of Sweden, residing at Grand Rapids, in the county of Kent and 5 State of Michigan, have invented new and useful Improvements in Latches for Refrigerator Doors and the like, of which the following is a specification.

The present invention relates to latches 10 for refrigerator doors and the like; and its object is, generally, to provide an improved device of that character whereby such doors may be securely and tightly held shut, and may nevertheless be easily opened.

15 This and any other and more specific objects hereinafter appearing are attained by, and the invention finds preferable embodiment in, the structure hereinafter particularly described in the body of this specification 20 and illustrated by the accompanying drawings, in which:—

Figure 1 is a front view of a latch carried by a swingable door and a keeper therefor carried by the jamb of the door, the 25 latch's casing being sectioned on line 1—1 of Figure 2;

Figure 2 is a top plan view of the same, the latch's casing being sectioned on line 2—2 of Figure 1;

30 Figure 3 is a sectional view of certain parts taken on line 3—3 of Figure 2;

Figure 4 is a sectional view of certain parts taken on line 4—4 of Figure 2;

Figure 5 is a sectional view of the same 35 parts seen in Figure 3 taken on the same line of section, but showing the latch bolt rotated about its longitudinal axis to another position; and

Figure 6 is a sectional view of the same 40 parts seen in Figure 4 taken on the same line of section, but showing the latch bolt rotated about its said axis to another position.

In the drawings, my improved latch is 45 shown mounted adjacent the free edge of a swingable refrigerator door 1, the keeper 2 of the latch being mounted on the jamb 3 of the door. The latching bolt 4 is mounted on the pivot pin 5 vertically-rockingly into 50 and out of latching engagement with the keeper, and has in addition to such rocking movement a rotative movement about its longitudinal axis into and out of resting position on a support or shelf 6 carried by

the door. The bolt is mounted on the pivot 55 pin sufficiently loosely to permit these movements. A guide member 7 is carried by the door and is disposed on the opposite side of the bolt's said axis from said support 6. This guide member is, in the construction 60 shown, the inner surface of the wall 8 of the latch's casing 9.

A spring 10 pressing between the bolt 4 at the point 11, and the casing 9 at the point 12, urges the bolt into latching engagement 65 with the keeper and also into its position of rest on the support 6. When the handle portion 13 of the bolt is drawn down by hand far enough, or when the door is pushed to nearly its closed position by the outer 70 end 14 of the bolt riding up on the inclined forward face 15 of the keeper, the free end 14 of the bolt rises against the pressure of the spring 10 until the under side 17 of the bolt reaches the level of the support 6, 75 whereupon the bolt is rotated about its longitudinal axis by the spring 10 until the under side 17 of the bolt engages and rests on said support. When however the door is pushed further toward shut position, the 80 inner side of the bolt strikes the keeper and the bolt is thereby oppositely rotated about its said axis sufficiently to cause its lower side to be moved outwardly and off of the support 6, so that the spring 10 may there- 85 upon press the outer end of the bolt into tightly latching engagement with the keeper. It will be seen that, in the construction shown, the bolt is given this rotative movement to release it from the support 6, by the 90 stationary guide member 7 against which bears the upward extension 16 of the bolt.

The positions of certain parts are seen in Figures 3, 4, 5 and 6. The spring 10 rotates the bolt on its longitudinal axis to the position seen in Figure 3, in which its lower side 17 is pressed into resting position on the support 6 as shown in Figure 4. When however the outer end 14 of the bolt strikes the keeper, the bolt moves off of this support in its oppositely rotative movement into which opposite rotative movement it is forced or guided by its upwardly-extending portion 16 which contacts with the bearing 7, the bolt now assuming the axially 100 rotative position seen in Figures 5 and 6.

It will be seen that the mere pressing of the bolt's handle portion 13 toward the door

has little or no effect to release the bolt from the support 6; but that it is the said axial rotative movement of the bolt caused by its striking against the keeper in the 5 door's closing movement, and the cooperating effect of the guide member 7, which effects the bolt's release from the support 6.

The invention being intended to be pointed out in the claims, is not to be limited 10 to or by details of construction of the particular embodiment thereof illustrated by the drawings or hereinbefore described.

I claim:

1. In combination with a keeper therefor, a door latch comprising: a bolt rockingly 15 movable into and out of latching engagement with the keeper, and having a rotative movement about its longitudinal axis into and out of resting position on the herein- 20 after mentioned support; a support; a guide member disposed on the opposite side of said axis from the support in the bolt's said resting position; the bolt being, guidedly by said member, movable from the 25 support by striking the keeper.

2. In combination with a keeper therefor, a door latch comprising: a bolt rockingly 30 movable into and out of latching engagement with the keeper, and having a rotative movement about its longitudinal axis into and out of resting position on the herein- 35 after mentioned support; a support; a guide member disposed on the opposite side of said axis from the support in the bolt's said resting position; a spring pressing the bolt into 40 said resting position; the bolt being,

guidedly by said member, movable from the support by striking the keeper.

3. In combination with a keeper therefor, a door latch comprising: a bolt rockingly 40 movable into and out of latching engagement with the keeper, and having a rotative movement about its longitudinal axis into and out of resting position on the herein- 45 after mentioned support; a support; the bolt being movable from the support by striking the keeper:

4. In combination with a keeper therefor, a door latch comprising: a bolt rockingly 50 movable into and out of latching engagement with the keeper, and having a rotative movement about its longitudinal axis into and out of resting position on the herein- 55 after mentioned support; a support; a spring pressing the bolt into said resting position; the bolt being movable from the support by striking the keeper.

5. In combination with a keeper therefor, a door latch comprising: a bolt rockingly 60 movable into and out of latching engagement with the keeper, and having a rotative movement about its longitudinal axis into and out of resting position on the herein- 65 after mentioned support; a support; a spring pressing the bolt into said latching engagement; the bolt being movable from the support by striking the keeper.

In testimony whereof I have hereunto set my hand at Grand Rapids, Michigan, this 29th day of May, 1924.

ANDREW EKMAN.
